J. B. ALLEN

EXERCISING MACHINE

Filed Nov. 21, 1921

FIG. 1.

UNITED STATES PATENT OFFICE.

JAMES B. ALLEN, OF BRIGHTON, COLORADO.

EXERCISING MACHINE.

Application filed November 21, 1921. Serial No. 516,800.

To all whom it may concern:

Be it known that I, JAMES B. ALLEN, a citizen of the United States, residing at Brighton, in the county of Adams and 5 State of Colorado, have invented certain new and useful Improvements in Exercising Machines, of which the following is a specification.

This invention relates to exercising machines and its main object is to provide a 10 mechanism of simple and practical construction for exercising the limbs and other parts of the human body in treating paralytic afflictions and other ailments of similar nature.

Another object of the invention is to provide in connection with apparatus of the above described character, an electric appliance to subject the afflicted part or 15 parts of the body to the stimulating effect of a current of electricity; further objects are to provide means for generating the electric current by the operation of the machine, and to connect in the circuit of 20 the generator, a variable resistance to regulate the current strength, and a switch to selectively connect different conductive parts of the machine in the circuit; and still other 25 objects reside in details of construction and a novel arrangement of parts, all of which 30 will fully appear in the course of the following description taken in connection with the accompanying drawing.

By the use of my invention any part of 35 the body may be developed and strengthened either by power exerted by the patient or through the medium of a suitable source of mechanical energy, and invalids who have 40 partially lost the power to move or control the movement of their limbs, as well as those who are completely incapacitated, may be beneficially treated by exercise and 45 electricity, the application of both of which is under full control of the operator.

In the drawings in the various views of 50 which, like parts are similarly designated,

Figure 1 represents a side elevation of my improved exercising machine;

Figure 2, an end elevation looking in 55 the direction of the arrow A, Figure 1, the hand grips forming part of the operating mechanism, having been shown in section; and

Figure 3, a diagrammatic representation

of the electric circuits and connections included in the invention. 55

Referring to the drawings, the numeral 2 designates a support preferably made in the form of an upholstered four-legged stool of strong and solid construction. 60

A frame 3 projecting forwardly of the stool and rigidly connected with the legs thereof, has bearings for the support of the fulcrum pin of an up and downwardly extending lever 4. 65

The lever is preferably composed of two connected metal bars, the lower portions of which, converge and extend outwardly at their extremities for the support of pedals or foot rests 5. 70

The pedals are designed to support the feet of a patient seated on the stool and they are movably connected with the laterally projecting ends of the lever by means of loops 6 of leather, rubber, or other flexible and non-conducting material. 75

Straps and heel rests on the pedals, are provided to hold the feet of the operator in place thereon and the loops 6 serve to resiliently mount the pedals on the lever, 80 as well as to insulate them from the conductive parts thereof.

Transverse hand-grips 7 at the upper end of the lever, are intended to be grasped by an operator occupying the seat and they 85 are composed of cylindrical cores of insulating material rigidly attached at opposite ends of the lever by a bolt 8, and sleeves of metal or other conductive substance, which are fitted on the cores in 90 spaced relation to the lever.

The lever is positioned relative to the stool so that a person seated thereon may comfortably impart an oscillating movement to the lever by means of either the 95 hands or the feet engaging with the grips or the pedals.

Arranged between the legs of the stool, beneath the seat, is a frame 9 for the support of the operating mechanism of the 100 machine. The mechanism comprises a crank shaft 10, a crank of which is connected with the lever by a bar 12.

The shaft carries a gear wheel 13 which meshes with a pinion 14 on a second shaft 105 15 provided with a combined pulley and balance wheel 16. The two shafts are rotatably supported one above the other in

boxes fastened upon parallel members of the frame.

5 Mounted upon a part of a base frame 17 extending rearwardly of the stool in rigid connection with the legs thereof, is a small generator of electricity 18 such as a magneto, the rotor of which is connected with the pulley on the shaft by means of a belt 19.

10 The base frame which rests on the floor at opposite sides of the stool, furthermore supports an electric motor 20, the rotor of which has a pulley for its driving connection with the pulley 16 through the medium 15 of a second belt 21. A four point switch 22 on the lever is connected in a circuit with the generator of electricity and a variable resistance 23 included in the circuit, provides a convenient means for varying the 20 strength of the current as it passes through the switch.

The switch may be of any conventional design to transfer the current flow between the hand grips and the pedals with which its 25 terminals are connected by means of conductors 24.

30 In the construction shown in the drawings, the connections are made by plugs at the ends of the conductors, that are inserted in the sockets of the parts. It will be understood without further illustration that one or more of the conductors may be connected to conductive plates or other electrodes for applying the current to parts of the body of 35 a patient, other than the limbs.

In the operation of my invention, a patient seated on the stool, imparts an oscillating movement to the lever by means of the arms or the legs and thereby gradually develops and strengthens any limb which by 40 motor paralysis or other similar disease, was deprived of its natural functions.

The movement of the limbs in unison with that of the oscillating lever, furthermore 45 gives activity to any internal organs which may be in an abnormal condition, and in general, strengthens and develops every muscle and organ of the body.

If the condition of the patient is such that 50 he can not exert the power required to operate the lever, the latter is moved through the medium of the motor until the invalid has regained sufficient strength to operate the machine by his own effort.

55 During the operation of the machine, a current of electricity of readily regulated strength is transmitted from the generator to the afflicted parts, it being understood that by means of the switch, the current may 60 be transferred from any part of the body to another.

It will be evident that the machine, as shown and described, is not only of use in restoring the health of invalids, but is also 65 of benefit to persons whose sedentary occu-

pations prevent them from taking sufficient exercise to maintain a normal physical condition.

Having thus described my invention, what I claim and desire to secure by Letters Patent is:

1. In an exercising machine, the combination with a support, of an oscillatory lever, hand grips and foot rests at opposite ends thereof, a source of electricity, and means for connecting the hand grips and the foot rests in circuit with said source.

2. In an exercising machine, the combination with a support, of an oscillatory lever, hand grips and foot rests at opposite ends thereof, a source of electricity, and means for selectively connecting the hand grips and the foot rests in circuit with said source.

3. In an exercising machine, the combination with a support, of an oscillatory lever, hand grips and foot rests at opposite ends thereof, a source of electricity, means for connecting said hand grips and foot rests in circuit with said source, and a switch adapted to adjust said connections for excluding any one of the parts from the circuit.

4. In an exercising machine, the combination with a support, of an oscillatory lever, hand grips and foot rests at opposite ends thereof, a source of electricity, means for connecting the hand grips and foot rests in circuit with said source, and a variable resistance in the circuit.

5. In an exercising machine, the combination with a support, of an oscillatory lever, hand grips and foot rests at opposite ends thereof, a rotary shaft in operative connection with the lever, a generator of electricity, and means for the operation of the generator by movement of the shaft.

6. In an exercising machine, the combination with a support, of an oscillatory lever, hand grips and foot rests at opposite ends thereof, a generator of electricity, means for operating the generator by movement of the lever, and means for conducting electric current produced by the generator to the hand grips and the foot rests.

7. In an exercising machine, the combination with a support, of an oscillatory lever, hand grips and foot rests at opposite ends thereof, a generator of electricity, means for operating the generator by movement of the lever, and means for conducting electric current produced by the generator to the body of the operator of the lever.

8. In an exercising machine, the combination of a seat, an oscillatory lever, having members to engage with limbs of a person occupying the seat, a motor in driving connection with the lever, a generator of electricity, means to operate the generator during movement of the lever, and means for transmitting electric current produced in the generator, to the body of the person.

9. In an exercising machine, the combination of a seat, an oscillating lever having parts for engagement with limbs of a person occupying the seat, a rotary shaft in operative connection with the lever, a balance wheel on the shaft, a motor in driving connection with the shaft, a generator of elec-

tricity having a driven connection with the shaft, and means for transmitting electric current produced in the generator, to the body of the person.

In testimony whereof I have affixed my signature.

JAMES B. ALLEN.
